ABSTRACT: In a furnace in which a workpiece is supported on hollow supporting members, a fluid heat transfer medium is circulated through a closed system which includes the hollow supporting members. The heat transfer medium which has a boiling point of at least 300° F. is introduced into the supporting member at a temperature of at least 300° F. and cooled when leaving the supporting members to a minimum temperature of 300° F. A pump is provided for circulating the heat transfer medium and a heat exchanger is provided between the exit side of the supporting members and the entry side of the pump. The medium in the closed system is preferably maintained at super-atmospheric pressures.

METHOD AND APPARATUS FOR HEATING A WORKPIECE

This invention relates to a method and apparatus for heating a workpiece and more particularly to the heating of steel billets, slabs, blooms or the like which pass successively through a heating chamber on hollow skid rails which extend substantially the length of the heating chamber. Each entering billet pushes the previous billets along the skids with hot combustion gases being introduced both above and below the skids. The billets are pushed from the end of the skids onto a refractory lined bottom of a heated soaking chamber at the exit end of the furnace. The most common practice is to water cool the skids which results in a lower temperature in those parts of the billet which rest on the skids. In some instances this results in imperfections in the rolled product. To reduce or eliminate these skid marks some furnaces have a plurality of longitudinally extending tunnels within the soaking chamber beneath the skid marks with hot combustion gases passing through the tunnel. When open top tunnels are used they are soon filled with scale from the billet which require shutdown of the furnace for removal. When refractory covers are provided for the tunnels, the billets break or wear away the covers to such an extent that the tunnels are also filled with scale. According to my previous U.S. Pat. No. 3,212,763 dated Oct. 10, 1965, the skids are air cooled rather than water cooled which permits the surface of the skid that contacts the billet to attain a higher temperature so as to minimize the temperature differential. This provides for more uniform heating of the billets, but more careful control is required to prevent overheating of the skids. Also, the system to be economical requires that the heated air from the skids pass to recuperators to heat the combustion air or directly to the burners as combustion air. This requires a complicated system.

It is therefore an object of my invention to provide a furnace in which the skids are cooled with a cooling liquid having a boiling point substantially above that of water so as to permit higher and more uniform skid temperatures.

Another object is to provide a method of operating a furnace utilizing a heat transfer medium having a boiling point of at least 300° F. in which the temperature of the medium entering and leaving the hollow skids is accurately controlled.

These and other objects will be more apparent after referring to the following specification and attached drawings, in which:

FIG. 1 is a schematic sectional elevation of a reheating furnace of the general type shown in my above-mentioned patent;

FIG. 2 is a view taken on the line II-II of FIG. 1;

FIG. 3 is a view taken on the line III-III of FIG. 1; and

FIG. 4 is a schematic view of the cooling system for the furnace skids.

Referring more particularly to the drawings, reference numeral 2 indicates the heating chamber of a continuous reheating slab furnace having an entry door 4 and an exit door 6. Hollow skids 8 extend from the door 4 to a refractory hearth section 10. The skids 8 are shown as being made in three sections spaced along the length of the furnace with four skids arranged transversely of the furnace. This may be varied as desired since it has no relationship to the present invention. The skids 8 are connected to a coolant main 12 by means of vertical pipes 14 and transverse headers 16. The other end of the skids 8 are connected to a return main 18 by means of vertical pipe 20 and headers 22. The skids 8 are supported by transverse tubes 24 having one end connected to main 12 by means of vertical pipes 26 and the other end connected to return main 18. The transverse pipes 24 are supported by pipes 28 bent into the form of an inverted U. As shown in FIG. 3 one end of each pipe 28 is connected to main 12 and the other end to main 18.

Referring now to FIG. 4 the skids 8 and pipes 24 and 28 are shown schematically connecting the mains 12 and 18. A storage tank 30 provided with a heater 32 contains the heat transfer medium which is a liquid having a boiling point of at least 300° F. and preferably higher. A suitable, readily availa-

ble medium is HITEC manufactured by DuPont. This is a eutectic mixture containing 53 percent potassium nitrate, 40 percent sodium nitrate, and 7 percent sodium nitrate. Dowtherm A or Dowtherm E manufactured by Dow Chemical Company are also suitable, particularly the former. Dowtherm A is a eutectic mixture containing 26.5 percent diphenyl and 73.5 percent diphenyl oxide by weight. Dowtherm E has as its main ingredient O-Dichlorobenzene.

One side of a transfer pump 34 is connected to tank 30 through a conduit 36 having a valve 38 therein. The other side of the pump 34 is connected to the tank 30 by means of a bypass 40 having a valve 42 therein. Medium from the tank 30 is pumped to a pressure heater 44 through a conduit 46 having a valve 48 therein and through a conduit 50. Also connected to the pump 34 and conduit 50 is a conduit 52 having a valve 54 therein. The pressure heater 44 is provided with a burner 56 to which fuel is supplied through a thermostatic control valve 58. The pressure heater 44 is provided with a vent 60. A circulating pump 62 connected to the heater 44 is connected to main 12 through a shutoff valve 64. A valve controlled vent 66 is provided in the highest part of the coolant system. The return main 18 is connected to a heat exchanger 68, which in turn is connected to the pressure heater 44. Located in the line between the return main 18 and the heat exchanger 68 is a shutoff valve 70 and a back pressure valve 72. A bypass valve 74 is connected in parallel with back pressure valve 72. Cooling water is delivered to the heat exchanger 68 through a conduit 76 having a control valve 78 therein. The setting of the valve 78 is controlled by means of a thermostat 80 located between return main 18 and valve 70. A conduit 82 connects the return main 18 to the tank 30. Shutoff valve 84 and drain pump 86 are connected in series with conduit 82.

When the furnace has not been in operation for some time the heat transfer medium will be maintained at a temperature in the storage tank at a temperature between 53 and 100° F. To start the system the medium is first heated in the tank to a temperature preferably in the neighborhood of 45°. The vents 60 and 66 are opened, the valves 42, 48, 64, 70 and 74 opened, and the valves 38, 54 and 84 closed. The pump 34 then transfers medium from the tank 30 to the pressure heater expansion chamber 44 where it is heated to and controlled at 450° F. The pump 62 is started in operation to circulate the medium through the system at the same rate as the pump 34 pumps the medium from the tank 30. When the system is filled pump 34 is stopped so that no more medium is transferred into the system. The temperature of the medium in the heater 44 is increased to and maintained at about 500° F. which causes the medium to at least partially vaporize with the vapor driving all the air from the system. The vents 60 and 66 are then closed and the valve 74 also closed resulting in the medium being circulated at a preset back pressure between 130 and 145 lbs. per sq. inch. During the filling operation only a minimum water flow is passed through the heat exchanger 68. The furnace is now ready for firing and as the furnace heats up the medium is circulated at the above pressure and temperature. Eventually the furnace will be hot enough to heat the medium passing through the furnace to a temperature above 500° F. When the temperature of the medium in the return main 18 is above 750° F. the valve 78 will be controlled by the thermostat 80 so as to maintain the temperature at 750° F.

When the furnace is shut down for a short time the bypass valve 74 is opened when the temperature of the medium decreases below 450° F. so as to decrease the circulating pressure in the system. The temperature regulators and the pressure heater 44 and heat exchanger 68 will be set to maintain a circulating temperature of 450° F. during the furnace shutdown. When it becomes necessary to transfer the medium from the furnace to the storage tank 30 for longer shutdowns, bypass valve 74 will be opened when the medium temperature is below 450° F. When the temperature of the medium in the system decreases to about 250° F. the vent 66 is opened, the valves 64, 42 and 48 closed and valves 38 and 54 opened. The pump 34 is then operated to transfer the medium from the

heater 44 to the storage tank 30. After the heater 44 is emptied the shutoff valve 36 is closed and the low points of the system are drained by closing the valve 38 and opening the valve 84 and operating the drain pump 86 to deliver the medium through bypass 40 to the tank 30. When it is desired to again start the system the procedure is as described above.

While one embodiment of my invention has been shown and described, it will be apparent that other adaptations and modifications may be made.

I claim:

1. The method of operating a furnace in which a workpiece is supported on hollow supporting members, which method comprises circulating a fluid heat transfer medium through a closed system including said hollow supporting members, said medium having a boiling point of at least 300° F., introducing said medium into said supporting member at a temperature of at least 300° F., and cooling said medium leaving said supporting members to minimum temperature of 300° F. before returning it to said supporting members.

2. The method of claim 1 in which said medium is circulated at a pressure substantially above atmospheric pressure.

3. The method of claim 2 in which said medium is circulated at a pressure between approximately 130 and 145 pounds per sq. inch and is at a temperature not in excess of approximately 750° leaving the said supporting members.

4. The method of claim 3 in which said medium is introduced into said supporting members at a temperature of

approximately 500° F.

5. In a furnace for heating a workpiece supported on hollow supporting members, the improvement comprising a closed cooling system including said supporting members, a pump for circulating a fluid heat transfer medium having a boiling point of at least 300° F. through said cooling system, and a heat exchanger between the exit side of said supporting members and the entry side of said pump.

6. The combination of claim 5 including a back pressure valve in said closed cooling system to maintain said medium at superatmospheric pressure.

7. The combination of claim 5 including a heater for said heat transfer medium in said closed cooling system, a storage tank for said medium, and a transfer pump for transferring medium from said tank to said heater.

8. The combination of claim 7 including means for controlling flow of a coolant to said heat exchanger, and means operable by the temperature of said medium leaving said supporting members for operating said flow controlling means.

9. The combination of claim 7 including a back pressure valve in said closed cooling system to maintain said medium at superatmospheric pressure, a bypass around said valve, and a control valve in said bypass.

10. The combination of claim 9 including means for draining the medium from said closed cooling system and returning it to said storage tank.
